[57] CLAIM

The ornamental design for a surface configuration of a hood for a vehicle, as shown and described.

DESCRIPTION

FIG. 1 is a front view of a surface configuration of a hood for a vehicle according to my novel design;

FIG. 2 is a top view of a surface configuration of a hood for a vehicle according to my novel design;

FIG. 3 is a left side view of a surface configuration of a hood for a vehicle according to my novel design, the right side view being mirror symmetrical; and,

FIG. 4 is a perspective view from the top left of a surface configuration of a hood for a vehicle according to my novel design, the perspective view from the top right being mirror symmetrical.

The broken lines shown in all drawing views are for illustrative purposes only and form no part of the claimed design.
